CLAIM

We claim the ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon in accordance with a first embodiment of the claimed design; and,

FIG. 2 is a front view of a display screen or portion thereof with icon in accordance with a second embodiment of the claimed design.

The broken line shown in each of the figures illustrates portions of the display screen or portion thereof with icon, and forms no part of the claimed design.
